(57) **CLAIM**

The ornamental design for a blind fabric, as shown and described.

DESCRIPTION

FIG. 1 is a perspective view of a blind fabric showing my new design;

FIG. 2 is a front elevational view thereof, the rear view being a mirror image;

FIG. 3 is a left side elevational view thereof, the right side being a mirror image;

FIG. 4 is a top elevational view thereof, the bottom view being a mirror image; and,

FIG. 5 is a perspective view of the blind fabric shown retracted and in a position of use.

The broken lines shown in FIG. 5 depict environmental subject matter that forms no part of the claimed design.
